UNITED STATES PATENT OFFICE.

FERDINAND M. RAUSCHER AND LOUIS REXROTH, JR., OF INDIANAPOLIS, INDIANA;
SAID RAUSCHER ASSIGNOR TO LOUIS REXROTH, SR., AND LOUIS REXROTH, JR.,
COPARTNERS TRADING AS R. R. MFG. CO., OF INDIANAPOLIS, INDIANA.

MACHINE FOR MAKING CLOTHES-HANGERS.

1,127,515.

Specification of Letters Patent.

Patented Feb. 9, 1915.

Application filed February 17, 1914. Serial No. 819,167.

To all whom it may concern:

Be it known that we, FERDINAND M. RAUSCHER and LOUIS REXROTH, Jr., citizens of the United States, residing at Indianapolis, in the county of Marion and State of Indiana, have invented certain new and useful Improvements in Machines for Making Clothes-Hangers, of which the following is a specification.

With the rapid growth and extension of the clothes cleaning business, a large demand for clothes hangers has arisen.

This invention relates to a machine for the manufacture of clothes hangers; and the object of the invention consists in the provision of a machine of the above character which, in addition to its simplicity of construction and efficiency of operation, can be manufactured and sold at a nominal price to enable the proprietor of the most modest cleaning establishment to own one of the machines.

A further object of the invention consists in the provision of a machine of the above character on which unskilled labor around the cleaning establishment can, at odd times, be employed in the manufacture of the necessary hangers.

We accomplish the above objects of our invention by means of the construction illustrated in the accompanying drawings, forming a part hereof, in which—

Figure 1 is a top or plan view of our machine for the manufacture of clothes hangers. Fig. 2 is a side elevation of said machine. Fig. 3 is a cross section of the upper portion of the machine, on the line 3—3 in Fig. 1. Fig. 4 is an enlarged detail sectional view, on the line 4—4 in Fig. 1. Fig. 5 is a side elevation of one of the hangers in a partially completed condition. Fig. 6 is a top or plan view of the hanger shown in Fig. 5, said view being taken along the dotted line 6—6. Fig. 7 is a view similar to Fig. 6, except that the hanger is in a more advanced state of completion. Fig. 8 is a view similar to Fig. 7, except that the hanger is shown in a completed condition.

Referring to the drawings, the machine comprises a supporting frame of the angle-iron uprights 10 forming the legs for supporting the table top 11. In order to add rigidity to the uprights 10 they are tied together by means of suitable braces 12 and

13. The table top 11 forms a platform upon which the devices for manufacturing clothes hangers are secured. The clothes hangers are made of suitable wire 14 bent over a former comprising a plate 15 suitably secured to the table top 11 at one end of said top. The wire 14 is purchased in the usual form of rolls, one of which is placed upon a receiving reel 18 which is supported at one end of the machine by the uprights 10. This reel rotates freely to enable the wire to pay out at which time it is cut into uniform lengths, each section of wire cut being of sufficient length to form a complete hanger. To insure each section cut from the roll to be of uniform length we provide a receptacle 23 into which the free end of the wire 14 is introduced until the end of the wire contacts the end of said receptacle, the distance between the end of the receptacle and the cutter device being such that a piece of wire 75 conforming to this intervening space will be sufficient to form a complete hanger. It will be noted that the receptacle 23 is formed on a curve, the object being to conserve the curvature of the wire as it comes from the 80 roll for, in a manner, it coincides to the curved rib 20 and, therefore, materially assists the operation of bending the wire in forming the hanger.

The forming plate 15 is provided with a 85 projecting circular rib 25 around which the wire is initially bent to form the hook 25^a by which the hanger is suspended. To one side of the rib 25 is the rib 26 which is sufficiently removed from the rib 25 to leave an 90 intervening space adapted to receive and hold the end of the wire 14 during the operation of bending the same into a hanger. As the wire leaves the rib 25 it passes across the front edge of the rib 24 which forms the 95 neck of the hanger and thence passes over the outer curved surface of a two-part curved rib 20 upon which the body of the hanger is formed. The front edge of said rib 24 is arranged to stand parallel with a 100 line passing through the transverse center of the plate 15 and circular rib 25. The rib 20 is remotely located from the rib 25 and extends an equal distance on each side of a line extending through the transverse center of the plate 15 and rib 25. The wire passes over the outer curved surface of the rib 20 and extends horizontally from

one end of the rib to the other, and this horizontal portion of the hanger is held in alinement by means of the ribs 22 and affords the means for supporting the trou-
5 sers. When the hanger is removed from the former the free end of the wire is left dis-
connected, as shown in Figs. 5 and 6, and this free end is then inserted into the aperture 27 in the margin of the plate 15 and is
10 formed into a hook 28. See Fig. 7. The hanger is now passed into the slot 30, in the plate 15, the hook 28 being brought into line and acted upon by means of a movable plunger 31, whereby the hook 28, as shown
15 in Fig. 7, is bent around the neck of the hanger and against the curved body thereof, as shown in Fig. 8 of the drawings.

As shown in Fig. 4 of the drawings, the plunger comprises a movable bar 31 which
20 passes through suitable apertures 32 in the lugs 33 formed integrally with the plate 15, and said plunger is moved forward to close the hook in the wire 14 by means of a bell-
crank 36 which is pivoted at 37 to the plate
25 15. The rear end of the lever 36 terminates in an arm 40 which contacts the end of the plunger 31, and said plunger is normally held in a retracted position against the lever 36 and the front end of the plunger is nor-
30 mally held clear of the slot 30 in plate 15 by means of the spring 41. The lever 36 and plunger 31 are actuated by means of a foot-pedal 43 which is connected to the lever 36 by means of a connecting rod 44.
35 In order to make the machine compact and enable all of the work connected with the manufacture of clothes hangers to be performed on the same machine, we pro-
vide a cutter device comprising an upright
40 50 conveniently located on the upper sur-
face of the table top 11 so that as the wire 14 is paid off the reel 18 it is passed through an aperture 51 in said upright. The aperture 51 is best shown in Fig. 3 of the draw-
45 ings. A cutter bar 53 is pivoted at 54 to the upright 50, and said cutter bar may be lowered to sever the wire by means of a foot-
lever 56 which is connected to the cutter bar 53 by means of a connecting rod 58. The
50 cutter bar 53 is held in its uppermost position, leaving the aperture 51 normally ex-
posed, by means of a spring 59.

While we have described our invention

with more or less minuteness as regards de-
tails of construction and arrangement and 55 as being embodied in certain precise forms,
we do not desire to be limited thereto un-
duly or any more than is pointed out in the
claims. On the contrary, we contemplate
60 all proper changes in form, construction,
and arrangement, the omission of immate-
rial elements and the substitution of equiva-
lents, as circumstances may suggest or ne-
cessity render expedient.

Having thus fully described our said in-
vention, what we desire to secure by Letters
65 Patent, is—

1. A machine of the above specified class
comprising a supporting frame, a clothes
hanger former plate arranged on said frame,
70 a rib on said plate to form the supporting
hook for the hanger, a rib arranged at one
side of said first rib to provide an inter-
vening space to receive and hold the end of
the wire comprising the hanger, a curved
75 rib arranged to extend an equal distance on
both sides of said first rib and arranged re-
motely therefrom, and a rib located be-
tween the first-named rib and curved rib and
having its front edge extending parallel
80 with a line through the transverse center of
said first-named rib and said curved rib.

2. A machine of the above specified class
comprising a supporting frame, a clothes
hanger former plate arranged on said frame
85 and provided with an aperture near its mar-
ginal edge for bending the terminal end of
the wire into a hook, a curved rib on said
plate, a circular rib located remotely from
90 said curved rib and arranged centrally
thereto, a rib formed to one side of said cir-
cular rib for holding one end of the wire,
and a rib arranged between said circular
rib and curved rib, the front edge of said
95 last-named rib extending parallel with a
line passing transversely through the center
of the curved and circular ribs.

In witness whereof, we have hereunto set
our hands and seals at Indianapolis, In-
diana, this 10th day of February, A. D. one 100
thousand nine hundred and fourteen.
